UNITED STATES PATENT OFFICE.

JOHN E. THORNTON AND CHARLES F. S. ROTHWELL, OF MANCHESTER, ENGLAND.

POSITIVE STRIPPING-FILM FOR PHOTOGRAPHS.

SPECIFICATION forming part of Letters Patent No. 760,585, dated May 24, 1904.

Application filed March 20, 1900. Serial No. 9,464. (No specimens.)

To all whom it may concern:

Be it known that we, JOHN EDWARD THORNTON and CHARLES FREDERICK SEYMOUR ROTHWELL, British subjects, residing at Manchester, in the county of Lancaster, England, have invented certain new and useful Improvements 5 in Positive Stripping-Films for Photographs, of which the following is a specification.

This invention relates to improvements in 10 the production of direct positive photographs, (such as described in the specification of our earlier patent, No. 647,540.) Hitherto in the production of such direct positive photographs there has been used a sensitive gelatino-bromid 15 emulsion coated very thinly upon a base of opaque, black, or colored paper. After exposure the film is developed, fixed, whitened, washed, and dried, yielding a positive image, as seen by reflected light. This image is reversed 20 as regards right and left unless a reversing prism or mirror is used.

By this invention non-reversed or correct positive pictures can be obtained.

It consists, essentially, of a photographic 25 sensitive film, capable of being stripped from its base, mounted upon a base of black or colored paper, from which it can be readily removed and reattached to the same or another black or colored paper with the reverse side 30 to the paper after having been developed, fixed, and whitened.

Figure 1 is a sectional view showing the sensitive film. Fig. 2 is a sectional view showing the film being reversed by stripping from 35 its original backing.

In carrying out the invention we take a black, colored, or opaque paper base A and apply or spread over the surface of the same a suitable stripping medium B and over that 40 the sensitive emulsion C. The stripping medium may be rubber or collodion applied on a waterproof surface; but we prefer the material formed by dissolving and drying the aluminium or zinc salts of the fatty acids. 45 This preparation renders the black or colored paper base waterproof and serves the important double purpose of causing the film to adhere to the paper base during all the various operations and yet enables it to be readily 50 stripped therefrom when the finished picture

has been dried. The paper A with the stripping medium B may be coated direct with the sensitive gelatin emulsion C in a thin layer, or it may be first coated with a reinforcing medium D, such as gelatin, celluloid, or other 55 material to support the image, and when quite dry the sensitive emulsion C be coated thereon in a thin transparent layer.

The complete film made in the manner described above is exposed in the camera, developed, fixed, whitened, and washed. When the washing is complete, a piece of black or colored paper E, previously coated with gelatin, gum, or other suitable adhesive substance F, is pressed into contact with the face C of 60 the picture and the whole allowed to become quite dry. The picture is completed by merely pulling the two pieces apart when the picture attaches itself to the adhesive black or colored paper and is consequently reversed 65 during this operation.

The film may be first stripped from the black or colored paper base and then the reverse side applied and caused to adhere to the same or to another black or colored paper 75 base. The result is the finished picture.

The whole operations present no special difficulties and the picture is obtained direct with the minimum of trouble and without the intervention of negative-making and print- 80 making processes.

What we claim as our invention, and desire to protect by Letters Patent, is—

1. A photographic film comprising in its construction a dark-colored paper base, a 85 stripping medium applied to the surface of the paper base, a layer of a reinforcing medium to support the image applied over the stripping medium, and sensitive emulsion applied over the reinforcing medium forming a thick 90 layer capable of being removed from the colored base, substantially as described.

2. In a photographic film, the combination with a layer of reinforcing medium to support the image, and a layer of sensitive emulsion 95 thereon, and a base of dark-colored paper, of a stripping medium interposed between the reinforcing medium and the base, substantially as described.

3. In a photographic film the combination 100

with a layer of a reinforcing medium to support the image, and a layer of sensitive emulsion thereon, and a base of dark-colored paper, of a stripping medium interposed between the 5 reinforcing medium and the base, and a second piece of dark paper E coated with an adhesive coating to be applied to the face of the sensitive layer, substantially as described.

4. In a photographic film the combination 10 with a dark-colored paper base, and a stripping medium comprising a salt of a fatty acid dissolved and dried applied to the surface thereof, of a layer of a reinforcing medium applied over the stripping medium, and a 15 layer of sensitive emulsion adhering to the reinforcing medium substantially as described.

5. In a photographic film the combination

with a dark-colored paper base and a stripping medium of a salt of a fatty acid dissolved 20 and dried applied to the surface of said base, of a layer of a reinforcing medium applied over the stripping medium, a layer of sensitive emulsion adhering to the reinforcing medium, and a second piece of dark paper E to 25 be affixed to the face of the sensitive layer, substantially as described.

In witness whereof we have hereunto signed our names in the presence of two subscribing witnesses.

J. E. THORNTON.
C. F. S. ROTHWELL.
